UNITED STATES PATENT OFFICE.

HENRY SELBY HELE-SHAW AND FRANCIS LEIGH-MARTINEAU, OF LONDON, ENGLAND.

HYDRAULIC APPARATUS.

1,137,208.

Specification of Letters Patent. Patented Apr. 27, 1915.

Application filed March 11, 1911. Serial No. 613,806.

To all whom it may concern:

Be it known that we, HENRY SELBY HELE-SHAW and FRANCIS LEIGH-MARTINEAU, subjects of the King of Great Britain, and residing at No. 64 Victoria street, London, W. C., England, have invented new and useful Improvements in Hydraulic Apparatus, of which the following is a specification.

This invention relates to improvements connected with hydraulic apparatus and has reference particularly to cranes and lifts operated by continuously driven variable stroke pumps preferably of the type set forth in the specification of Letters Patent No. 12574/09, which automatically cease to circulate liquid when the pressure within the system reaches a certain predetermined limit.

Our invention consists primarily in the provision of a self-contained closed circuit crane wherein a continuously driven variable stroke pump or continuously driven variable stroke pumps is or are utilized to actuate separate mechanism for effecting separately or simultaneously as may be desired different distinct movements of a load.

An important feature of our invention broadly consists in providing said apparatus with means for insuring that the pump or pumps shall automatically cease to operate immediately the crane is left unattended and combining with such means a means for causing the pump or pumps to also automatically cease increasing pressure when the pressure within the system reaches a certain predetermined limit.

In order that our said invention may be more readily understood and carried into practice, reference is hereby made to the accompanying sheets of illustrative drawings wherein an example of our invention applied to the case of a crane is illustrated.

In these drawings Figure 1 is a side elevational view partly in section of a crane constructed in accordance with our invention. Fig. 2 is a rear elevational view thereof. Fig. 3 is a diagrammatic view illustrating the pipe system. Figs. 4 and 5 are elevational and plan views respectively of the safety control whereby the pump is automatically brought to its zero position when left unattended from any cause, and Fig. 6 is a sectional plan view on line A—A of Fig. 1 illustrating the sluing gear. Fig. 7 is a detail elevational view of the pressure regulating device shown in Fig. 1.

Referring to these drawings, the numeral 1 designates an hydraulic ram whose movement operates to raise and lower the load. The numeral 2 designates a variable stroke reversible rotary pump preferably of the type set forth in the specification of Letters Patent No. 12574/09 which pump is, when the apparatus is in operation, continuously driven by an electric or other motor 4. From one of the orifices of the pump 2 a pipe 3 (Fig. 3) leads to the ram 1 and thus the operation of the pump serves to transmit fluid under pressure to actuate the ram 1 and thus the ram will be raised or lowered according to the direction of flow of the liquid. From the other orifice of the pump a pipe 5 leads to a supply or make up tank 6. It will be understood that the movement of the ram 1 is therefore dependent on the position of the stroke varying ring of the pump 2, and this position can be adjusted at will by the operation of the wheel 8 whose screw-threaded spindle 9 is engaged in a tapped block 10 carried upon the upper end of an arm or lever 11, which latter is provided with a slot 12 at its lower end. The slotted end of the arm or lever 11 pivotally engages a pin or pivot 13 which pin or pivot is carried upon the upper end of a ram 14. The stroke varying ring of the pump 2 is pivotally connected as at 15 to the arm or lever 11. It will thus be clear that if the wheel 8 is rotated, the arm 11 will move about the pin or pivot 13, and thus stroke will be given to the pump and the direction of flow of the liquid will of course depend on the direction in which the said wheel 8 is rotated.

In the event of the pressure within the system becoming too great, such for instance as when the crane is overloaded, the eccentricity of the stroke varying ring of the pump 2 will be automatically reduced by the rising of the ram 14 to which the liquid under pressure has access through a suitable pipe (not shown). As the pressure in the system rises, the ram 14 also rises in opposition to the safety spring 16 which surrounds a rod 17 and is located between the projections 19 of the support 20 and the head of the ram 14. As the ram 14 rises, the pin or pivot 13 travels along the slot 12 and reduces the stroke of the pump until, when the pin or pivot 13 has reached a position in line with the pin 15 by which the stroke varying rod of the pump is loosely connected prefer-

ably in a slot to the arm 11, the pump will cease to transmit liquid, its stroke varying ring being in the zero position. Of course this safety device does not necessarily always return the stroke varying ring of the pump 2 to its zero position but only moves the ring sufficiently to alter the stroke of the pump to that at which the pump is capable of effectively overcoming the load, the safety spring 16 being such as to offer a sufficient resistance to insure the continuous working of the apparatus under normal loads. That is to say, the stroke of the pump is only reduced when the pressure within the system becomes excessive. Of course although described particularly in relation to a crane, the foregoing mechanism may be equally well applied in any case where it is required to move a ram to overcome resistance.

20 In the case of the crane the subject of this particular example, the pump 2 and its controlling mechanism is carried upon a platform 21 which is capable of rotation in company with the ram about the ball bearings 22. The rotation of the crane is effected by the sluing gear comprising a separate secondary pump 23 in line with the pump 2 and driven by the same shaft and operating an hydraulic motor 24 located in the base.

25 The direction of flow of the liquid is determined by the position of the stroke varying ring within the secondary pump as is also the rate of flow. The rod 23^a of this secondary pump is spring controlled or provided with some other means for insuring the stroke varying ring normally remaining in its zero position so that the pump only has "stroke" while the lever is held over by the operator. The fluid pressure is

30 transmitted through a system of pipes as shown in Figs. 2 and 3 to the motor 24 which comprises a plurality (in this case three) of tubular pistons 25 arranged radially around the distributing valve 26. The valve 26

35 consists of an internal cylinder provided with ports 27, either of which act alternately as inlet and outlet ports to and from the motor, their particular functions being of course determined by the direction of flow of the liquid. These ports are connected by bores 34, 36 in said cylinder one to each side of the central distributing chest 26^a of the pump 23. Over the tubular pistons 25 are placed cylinders 29 which are closed at

40 their outer ends and fitted with sufficient accuracy over said pistons as to afford a sufficiently liquid-tight joint for practical purposes. These cylinders are constrained to move in a radial direction only, by the

45 rollers 29^a, which are confined within guides formed by the edges of the blocks 30 secured to the base of the crane. Above the cylinders a circular disk 31 is arranged eccentric to the center of rotation of the motor and

50 this eccentric disk is provided around its

edge with a path 31^a against which the rollers 29^a operate. The sleeve 31^b integral with or connected to the disk 31 is secured at its upper extremity to the platform 21 with which it rotates. One of the pistons 25 is always situated over or practically over one of the ports 27 which will be readily seen on reference to Fig. 6 of the drawings. When a pressure is exerted in the system one of the cylinders 29 according to the direction of flow, will exert a pressure on the path 31^a which will, if the pressure be sufficiently great, cause the path to revolve together with the distributing valve 26 about the center of rotation of the motor until the center line of the cylinder and piston in question is coincident with the line passing through the center of rotation and the center of disk 31. This operation is repeated by each cylinder so long as the pressure is maintained. When the cylinders have reached the end of their stroke they exhaust into the opposite port.

The fluid circuit of this motor is shown in Figs. 1, 2 and 3. Referring to Fig. 3, one side of the distributing chest 26^a of the pump 23 is connected to the pipe 32 which is connected at 33 (Fig. 1) to the bore 34 which leads to one of the valve ports 27. The other side of the distributing chest 26^a is connected to the pipe 35 which leads by way of the bore 36 (Fig. 2) to the other port 27. When the fluid is forced by the pump 23 through the pipe 32 it enters the lower one of the ports 27 shown in Fig. 6, and is exhausted into the upper one and the crane is rotated in a clockwise direction. The reversal of direction of the fluid in the system will reverse the functions of the ports 27 and cause the crane to rotate in the other direction. The liquid returns to the pump 23 by way of the bore 36 and the pipe 35. Leakage in the circuit is made up by suction of fluid from the tank 6. This is effected through the pipes 37 and 38 which are fitted with non-return valves 39 and 40 which prevent return of liquid to the tank 6. It is obvious that liquid can only be drawn in on the suction side of the pump, therefore two pipes 37, 38, must be provided which are employed alternately with the reversal of the flow.

Except for cranes where the lift is small, it would not be practicable to connect the ram to the load by the usual flexible connection passing over the pulley at the end of the jib without the interposition of some form of multiplying gear. In the example shown, the velocity ratio of the ram to the load is as one is to four. This ratio is obtained by providing upon the ram a pair of pulleys 41, 42, loose upon the spindle 43. The chain 44 or its equivalent is led along the jib to the pulley 45 under which it passes and is then conducted over the pulley 41 136

under the pulley 46 whence it is led over the pulley 42 and secured to the lug 47 upon the cylinder 1.

In Figs. 4 and 5 we have shown a form of the safety controlling gear which has the advantage that in addition to its automatically operating to prevent excessive pressure within the system, it also automatically operates to stop the working of the crane, if the latter is left unattended and whether overloaded or not. If there should be leakage in the system the pump will, however, continue to work just sufficiently to compensate for this leakage and thus the load can be maintained in any position.

This apparatus comprises a control lever by which the direction and speed of the crane is controlled and means whereby said control lever is returned to its initial position or that position where the pump stroke will be just sufficient to maintain the load against leakage upon the failure of the operator to continue a certain operation and also when the pressure within the system reaches a certain limit. In the construction shown the operation necessary to insure the working is to maintain in its lowermost position or thereabout the pedal 48 against the influence of the spring 48^a which is attached at one end to said pedal 48 and at the other to the ram 49 to which the pedal 48 is pivoted at 50. The ram 49 and pedal 48 operate in connection with mechanism herein-after described to prevent the pressure within the system from rising beyond a certain limit. The movable member of the ram 49 is extended downwardly through a bracket 82 which is shown in Fig. 4, as depending from the base 21. A nut is shown on the lower end of the movable member below the bracket so as to limit the upward movement thereof. A lug 81 is also shown on the movable member of the ram in Fig. 4 and a coil spring 80 is arranged around the movable member between the lug 81 and the bracket 82 so as to yieldingly thrust the movable member upwardly. The fixed part or casing of the ram 49 is connected to the pump 2 in any suitable manner. When the pressure of the liquid delivered by said pump reaches a certain limit, the spring 80 is overcome and the movable member of the ram forced downwardly so that the pedal 48 strikes the stop 51 so as to turn the pedal in the clockwise direction when viewed as in Fig. 4. The effect of turning the pedal 48 as first mentioned, is to thrust the link 73 to the right and by thus moving the link 73, the liquid thrown by pump 2 is reduced in a manner subsequently described.

The stop 51 limits the movement of the pedal 48. The control lever 52 is keyed upon the rotatable shaft 52^a supported by the standard 54 and is coupled by the link 52^b to the guide bar 2^a which operates the ad-

justable stroke controlling ring of the pump 2. The speed and direction of the working of the pump 2, and consequently of the crane also, is regulated according to the direction in which the lever 52 is thrown. It is essential that the lever 52 be not secured in any position by mechanical means, but merely held over by the operator. Upon the shaft 53 (Fig. 5) is mounted a bell crank lever the approximately horizontal arm of which is bifurcated to form two blades 55 and 56. Between these blades 55 and 56, passes a swinging bar 57 pivoted at 58 to the ram 1 of the crane. This swinging bar is partially embraced by a pair of blocks 59 which are provided with grooves in their opposing faces to receive said bar, and upon their outer faces are trunnions 60 which are journaled in the blades 55, 56. A rod 62 serves to connect the vertical arm 61 of the bell crank lever by means of the pin 64 to an extension 63 of the shaft 52^a. The blades 55 and 56 are normally drawn toward one another by the spring 65, so that the blocks 59 are caused to clamp the swinging bar 57. The force exerted by the spring is transmitted by the rod 69 which passes freely through the blades 55 and 56 to the point 70 upon the lever 66, the lever 66 being pivotally mounted between lugs 66^a carried on the bell crank member 55. This force is translated into the opposite direction by the short end 71 of the lever 66 by means of the bolt 72 which operates with the aid of the nut 72^a to draw the blade 56 toward its companion 55. The force exerted by the bolt 72 is increased by a multiple determined by the ratios of the effective lengths of the lever 66 upon either side of its fulcrum. The short arm of pedal 48 is pivotally and operatively connected to a bar 73 which rests upon the shaft 53 and is restrained by the collar 74. Upon the end of this bar is an incline 75 which bears against a roller 76 upon the extremity of the lever 66.

Before the operator can move the lever 52, which action must be performed to cause the crane to work, it is necessary to depress the pedal 48 which action causes the bar 73 to be drawn over, and the roller 76 to roll along the incline 75 thus rotating the lever 66 in opposition to the force exerted by the spring 65 and relieving the pressure of the blocks 59 against the swinging bar 57 by freeing the blade 56 from the influence of the force exerted by the bolt 72. Having performed the foregoing operation, the operator can throw over the lever 52 until the necessary speed is attained but in the event of his releasing the pedal 48, it will rise under the influence of the spring 48^a thrusting the bar 73 back to its normal position when the spring 65 will again exert the necessary force upon the lever 66 to cause the swinging bar 57 to be clamped. The bell

crank member 61 will then be rotated about the shaft 53 by the motion of the ram 1 and return the lever 52 to its normal position as shown. The lever will rest in this position because as soon as it reaches it the stroke of the pump 2 will have been reduced to zero—assuming that there is no leakage in the system—and therefore no liquid will be circulated and as no expansion can take place owing to the liquid being practically incompressible, the ram or other moving parts of the apparatus will immediately come to rest. The stop 77 which is carried upon the lower end of swinging bar 57 serves to rock the bell crank members 55, 56 and 61 when the ram reaches its uppermost limit, thus stopping the crane. As before mentioned if there should be leakage in the system the stroke of the pump will not be reduced to zero but will be reduced until the pumping is just sufficient to compensate for the leakage. To cause the ram 1 to rise it is necessary to throw the lever 52 to the left (Fig. 4) and to the right to cause it to descend. Of course this controlling apparatus may be found useful for various forms of apparatus where a ram is operated by a variable stroke pump.

It may in some cases be desirable to provide for the elevating of the jib of the crane to different angles and this can be effected by means of a separate ram actuated by either a separate pump or one of the previously mentioned pumps—preferably that actuating the sluing gear—can be coupled up to this jib elevating ram and utilized for this purpose in a manner which will be apparent to those persons conversant with this class of apparatus.

Although it is generally more convenient to provide separate pumps for effecting the various operations, viz., operating the load, sluing and elevating the jib, it will of course be understood that a single pump can be utilized to perform all these operations so long as a suitable pipe system is provided.

What we claim is:—

1. Hydraulic apparatus comprising a motor, variable stroke reversible pumps continuously driven by the motor, means actuated by liquid circulated by one of the pumps for moving the load in one direction, means actuated by liquid circulated by another pump for moving the load in another direction, closed circuits including the pumps and the load moving means and means for controlling the pumps independ-

ently of each other, substantially as described.

2. In hydraulic apparatus wherein a continuously driven variable stroke pump operated to move a load, a safety device comprising the combination of means automatically operating to reduce the stroke of the pump when the pressure within the system reaches a predetermined limit, and means automatically operating to cause the pump to cease moving the load under all conditions when the apparatus is left unattended, substantially as described.

3. The improved hydraulic lifting and lowering apparatus comprising the combination of a continuously driven variable stroke reversible pump, a hydraulic ram in the pump circuit for raising the load, operable means for regulating and controlling the stroke of the pump and the direction of flow of the liquid, a safety device for automatically reducing the stroke of the pump when the pressure within the system rises beyond a certain limit and a safety device for automatically reducing the stroke of the pump to zero or that at which the load is held stationary when the apparatus is left unattended.

4. In apparatus of the kind set forth, the sluing gear comprising a continuously driven variable stroke rotary pump, a hydraulic apparatus associated with the pump for bodily rotating the lifting apparatus and means for controlling the stroke of the pump and the direction of flow of the liquid to the apparatus for causing the rotation whereby the direction and degree of rotation of the lifting apparatus is regulated and controlled.

5. In a hydraulic crane apparatus in combination, a revoluble vertical standard, pumping apparatus carried by said standard, a load lifting device also carried by said standard, a motor for sluing said standard, connections between said pumping apparatus and said device and motor, and means for controlling said apparatus whereby said device and said motor can be operated independently of each other.

In testimony whereof we affix our signatures in presence of two witnesses.
